DESIGN FOR A TOASTER OR SIMILAR ARTICLE

William Geller, New York, N. Y.

Application August 21, 1946, Serial No. 132,694

Term of patent 3½ years

(Cl. D81—10)

To all whom it may concern:

Be it known that I, William Geller, a citizen of the United States of America, residing in New York city, county of New York, and State of New York, have invented a new, original, and ornamental Design for a Toaster or Similar Article, of which the following is a specification, reference being had to the accompanying drawing, forming part thereof.

Fig. 1 is a front perspective view of a toaster or similar article showing my new design.

Fig. 2 is a fragmentary view of the front portion in open position. The back is conventionally plain.

I claim:

The ornamental design for a toaster or similar article, substantially as shown and described.

WILLIAM GELLER.
